ELASTIC FABRIC

Richard M. Foster, Camden, N. J., assignor to
Hastings & McIntosh Truss Company, Philadelphia, Pa., a corporation of Pennsylvania

Application September 4, 1936, Serial No. 99,471

4 Claims. (Cl. 66—189)

This invention relates to an elastic knitted fabric adapted primarily for use in the manufacture of personal garments and surgical appliances including girdles, corsets, arm, leg, knee, elbow, 5 wrist, ankle and abdominal bandages, or in an article where a natural curvature is desirable, or in an article which will be subject to bending during use.

One object of the present invention is to provide an elastic fabric wherein one portion or area thereof will be relatively shorter, in a walewise direction, than another adjacent or surrounding area; and wherein the foreshortened and normal areas will be collectively composed of successively 10 knit courses of regularly formed stitches respectively extending uninterruptedly through said normal and foreshortened areas, with a rubber strand laid in each course or in relatively spaced courses.

Another object of the invention is to construct the fabric in such a manner that the rubber strands will be maintained in a common plane throughout the whole of the fabric, including the normal and relatively foreshortened areas, without being staggered or overlapping to effect the 20 foreshortening.

Another object of the invention is to construct a garment of the above noted fabric, in either a circular form, as could be knit on a circular knitting machine, or in a flat form, as could be knit on a flat knitting machine, or wherein the flat knit fabric would be provided with oppositely disposed edges arranged to be permanently or temporarily joined together to form a circular garment, and in either case to position the foreshortened area in such relation to the normal area as to provide a natural curvature in the tube or band so formed to cause the article to fit comfortably, for example, to position the foreshortened area at the various joints in those parts of the anatomy about which such articles are adapted to be applied. In cases where the article would be applied to the ankle or knee joints the foreshortened area, in the case of the ankle, 40 would be positioned in front of the ankle, i. e. across the instep; whereas, in the case of the article being applied to the knee joint, the foreshortened area would be positioned behind or at the bend of the knee, in either case facilitating the bending of the limb at the joint encased by the article.

Another object of the invention is to produce a natural curved or foreshortened area and/or welt or marginal area in a garment such as a limb 50 bandage, wherein the foreshortened areas will

have the same general appearance as the normal areas of the garment, whereby the presence of the garment, when worn, for example, under sheer hosiery, will not be rendered conspicuous, as frequently occurs when such articles are composed of different stitch formations in the different areas respectively of the garment. 5

The construction of the fabric and its use in specific forms of bandages will be fully disclosed hereinafter, reference being had to the accompanying drawings; of which:

Fig. 1 diagrammatically illustrates what is generally referred to as a surgical stocking with the garment composed of fabric made in accordance with the principles of the present invention; 15

Fig. 2 is a similar view illustrating what is normally referred to as a knee bandage; and

Fig. 3 diagrammatically illustrates the stitch formation of the fabric and the manner in which a predetermined area thereof is foreshortened 20 walewise with respect to an adjacent or surrounding area in accordance with the principles of the present invention.

The fabric shown in Fig. 3 is of the rib type, i. e. it is composed of a plurality of stitch wales 25 a, a formed on one set or bank of needles, such, for example, as the cylinder needles of a circular knitting machine, whereby the stitch wales a, a would lie on one face, for example, the outer face of the fabric, and a series of stitch wales b, b 30 formed on another set of needles, such, for example, as the dial needles of a circular knitting machine, whereby the stitch wales b, b would be disposed on the opposite or back face of the fabric. For the purpose of illustration and differentiation 35 the wales a, a will hereinafter be referred to as the outside wales and the wales b, b as the inside wales of the fabric.

In the present illustration of Fig. 3, the fabric shown is what is commonly referred to as a two-to-one rib, i. e. the outside wales a, a are arranged in pairs with single inside wales b disposed intermediate the pairs of outside wales. It will be understood, however, that the invention is not restricted to the use of a two-to-one rib and may 45 be constructed of one-to-one or two-to-two rib fabric, etc., wherein the inside wales alternate singularly or in pairs or in odd numbers with corresponding or different numbers of inside wales. 50

The stitch wales a, a and b, b are formed as the result of knitting successive courses of stitches coordinately on the two banks of needles with the stitches of each course interlooped with the 55 stitches of a preceding and a succeeding course.

- to form a complete fabric. Such a plurality of courses is illustrated at 1 to 15 inclusive in Fig. 3. Each of the courses 1 to 15 is continuous throughout the width or circumference of the fabric and in each course, in the present instance, is laid an elastic thread c which may be of either bare, cut or extruded rubber or latex, or a similar strand provided with a spiral covering of fibrous thread as is common in articles of the types noted.
- 10 As shown in Fig. 3, the fabric may, according to the principles of the present invention, include normal areas A, A¹, A², and A³ disposed respectively at the opposite sides and at the top and bottom of and surrounding the foreshortened area B. The stitch formation in the areas A, A¹, A², and A³ is of the usual regular common stitch type, and wherein all of the stitches 16, in each of the successively knit and interlooped courses, are of a uniform predetermined length, which 20 normally would produce an ordinary common knitted fabric which would be of uniform shape and appearance throughout its length and breadth or circumference when composed entirely of such uniform regular stitches.
- 25 The walewise foreshortening of the area B, according to the principles of the present invention, is effected by producing relatively shorter regular common stitches 17, in alternate or in relatively spaced courses, in a predetermined 30 number of immediately adjacent wales. For example, the unevenly numbered courses 1, 3, 5, etc. are of regular length stitches 16 and the evenly numbered courses 2, 4, 6, etc. are of shortened length stitches 17, course 1 being the 35 last course in the normal area A³ while course 15 forms the first course in the normal area A².
- The sum of the difference between the collective lengths of the stitches in the successive courses in the normal areas and the collective 40 lengths of the stitches in the foreshortened area determines the extent to which the area B would be foreshortened with respect to the adjacent areas A, A¹, for example.
- In the present instance, the shortened stitches 45 17 are formed in alternate courses throughout the length of the area B as noted above. However, it is within the scope of the present invention that the courses containing the shortened stitches may be spaced as desired, for example, in every third or fourth course, etc.
- The shortening of the stitches 16 in predetermined courses may be readily effected during the knitting of the fabric by tightening or increasing the tension on the knitting thread at 50 predetermined intervals as the thread guide moves past predetermined needles or as said needles move past said thread guide, as the case may be, and applying normal tension to the thread during relative movement between the 55 thread guide and the needles adapted for knitting those areas adjacent to the foreshortened area.
- The knitting of relatively short regularly shaped stitches 17 in a group of immediately adjacent wales, including both the inside and outside wales, produces the effect of foreshortening those particular wales with respect to the wales in the adjacent normal areas composed solely 60 of the regular shaped and lengthened stitches 16.
- 70 The shortening of stitches in predetermined courses does not materially affect the coursewise elasticity of the fabric, for the reason that when the fabric is stretched coursewise the short stitches being under abnormal tension tend to straighten out coursewise of the fabric, and in

so doing draw the stitches of the immediately preceding and immediately succeeding courses, which are of normal length, together, producing a compensation uniformly throughout the foreshortened area.

5 A practical application of the fabric shown in Fig. 3 is illustrated in Fig. 1 wherein the foreshortened area B is formed in the instep portion of a surgical stocking, such foreshortening of the fabric within said area producing a natural curvature in the front of the stocking, as illustrated at 18. In this application the marginal edges B¹ of the foreshortened area B are in the form of steps produced by varying the number of needles to which the thread under the above noted abnormal tension is fed during the knitting of different groups of successively knit courses and by periodically increasing, then periodically decreasing the number of needles so affected in succeeding groups of stitch courses.

10 In the application illustrated in Fig. 2, the foreshortened area B is disposed at the back of the knee band providing a natural curvature 19 at that portion of the band which would lie immediately behind the knee, or at the bend of 25 the knee. In this case, the marginal edges B² of the foreshortened area B are varied at each succeeding course, whereby different portions of the marginal edges B² are caused to lie at different angles with respect to the wales and 30 courses of the fabric.

15 In each of the instances of Fig. 1 and Fig. 2, the foreshortened area B is surrounded by normal areas A and A¹, at the opposite sides respectively of the area B, and at the top and bottom of said 35 area with normal areas A² and A³ respectively.

20 In each of the instances of Fig. 1 and Fig. 2, the upper portion of the garment illustrated is provided with a welt area C, wherein alternate courses, or otherwise relatively spaced courses, 40 are formed completely, from side to side or around the garment, of shortened stitches 17 and intermediate complete courses of normal length stitches 16.

25 The fact that the normal stitches 16 and the 45 shortened stitches 17 are of the same general regular common form and differ only in length, while they retain substantially the said width, produces a garment in which there is no material difference in the appearance between the area 50 composed of the normal length stitches and the fabric composed partly of normal length stitches and partly of the shortened length stitches, and what little difference in appearance may be apparent when the fabric is in a normally contracted condition disappears when the fabric is placed under slight lateral tension as when being worn. For these reasons the fabric under 55 conditions of use has a substantially uniform appearance throughout the garment and attracts 60 no undue attention when worn under an outer garment composed of thin sheer fabric.

65 While the shortening of the stitches 17 has been described as being effected by increasing the tension on the knitting thread as such stitches are being formed, it will be apparent that in machines of the independently movable needle type, on which such bandages, etc. are commonly or frequently knitted, the difference in the lengths of the stitches 16 and 17 respectively may be 70 produced by automatically or otherwise varying the position of the stitch cams with respect to the stitch casting point of the machines whereby a greater or lesser amount of knitting thread may be drawn by each needle or group of needles 75

as required and whereby the change from the normal length stitch 16 to the shortened stitch 17 and vice versa may be effected at will.

I claim:

5. 1. A tubular ribbed knit fabric comprising two laterally adjacent areas composed conjunctly of complete continuous successively knit courses of stitches forming inside and outside wales with rubber strands laid in predetermined courses between said inside and outside wales, said predetermined courses being composed of regular full length stitches loosely embracing the rubber strands in one of said areas and regular short length stitches tightly embracing the same rubber strands in the other of said areas, said fabric also including within and extending across said laterally adjacent areas in parallel interposed relation to said predetermined courses, additional courses composed solely of full length stitches 20 loosely embracing said rubber strands respectively laid in said interposed courses.

2. A tubular ribbed knit fabric comprising two laterally adjacent areas composed conjunctly of complete continuous successively knit courses of stitches forming inside and outside wales with rubber strands laid in predetermined courses between said inside and outside wales, said predetermined courses being composed of regular full length stitches loosely embracing the rubber strands in one of said areas and regular short length stitches tightly embracing the same rubber strands in the other of said areas, said fabric also including within and extending across said laterally adjacent areas in parallel interposed relation to said predetermined courses, additional courses composed solely of full length stitches loosely embracing rubber strands respectively laid in said interposed courses, said fabric at and beyond the opposite ends of said laterally adjacent areas including successive courses composed solely of full length stitches with rubber strands therein and loosely embraced thereby.

3. A tubular knit surgical stocking including a foot section, a leg section and a section intermediate said leg and foot sections, said intermediate section including a front area and a

laterally adjacent area at each side of said front area, said stocking being formed of ribbed knit fabric composed of complete continuous successively knit courses of stitches forming inside and outside wales with rubber strands laid in predetermined courses between said inside and outside wales, said predetermined courses being composed of regular full length stitches loosely embracing the rubber strands in said side areas and regular short length stitches tightly embracing the same rubber strands in said instep area, said stocking also including within and extending across said front and side areas in alternating relation to said predetermined courses, additional courses composed solely of full length stitches loosely embracing rubber strands respectively laid in said additional courses, and said stocking also including successively knit courses composed solely of full length stitches with loosely embraced rubber strands therein in said leg and foot sections at the opposite ends of said intermediate section. 20

4. A tubular knit surgical knee band comprising a front area and a back area formed of ribbed knit fabric composed of complete continuous successively knit courses of stitches forming inside and outside wales with rubber strands laid in predetermined courses between said inside and outside wales, said predetermined courses being composed of regular full length stitches loosely embracing the rubber strands in said front area and regular short length stitches tightly embracing the same rubber strands in said back area, said knee band also including within and extending across said front and back areas in alternating relation to said predetermined courses, additional courses composed solely of full length stitches loosely embracing rubber strands respectively laid in said additional courses, and said knee band also including successively knit courses composed of full length stitches with loosely embraced rubber strands therein in circumferential areas adjacent each of the opposite ends of said front and back areas.

RICHARD M. FOSTER.
